UNITED STATES PATENT OFFICE.

KARL RADOUSH, OF ST. PAUL, MINNESOTA.

FIRE ALARM AND SAFETY DEVICE FOR STABLES.

Application filed September 10, 1921. Serial No. 499,621.

To all whom it may concern:

Be it known that I, KARL RADOUSH, a citizen of the United States, residing at St. Paul, in the county of Ramsey and State of Minnesota, have invented a new and useful Fire Alarm and Safety Device for Stables, of which the following is a specification.

My invention relates to devices for saving horses and other animals from stables in case of fire; and the broad object is to provide a stable with automatic means which will open the stable door, release the animals and drive them out, tend to extinguish the fire and also sound an alarm for help, all in an automatic manner.

In the accompanying drawing:

Fig. 1 is a front elevation of a barn or stable having a hayloft and being equipped with my device.

Fig. 2 is a top or plan view of the stable in Fig. 1 with the roof, hayloft and a few other things omitted.

Fig. 3 is a section on line 3—3 in Fig. 2 showing more clearly the arrangement of the alarm bell.

Fig. 4 is a section on line 4—4 in Fig. 2 with a fragment of the hayloft and barn roof restored.

Fig. 5 is a fragmentary top view of the staple and hasp holding the door shut.

Referring to the drawing by reference numerals, 1 designates the floor, 2 the walls and 3 the roof of a stable having above it a hayloft 4 with door 5. The stable I have shown is small and in every way limited to only what is necessary to an understanding of any size stable equipped with my invention no matter what its size may be.

In Figs. 2 and 4 I have shown along one wall of the stable a series of mangers 5^a separated by partitions 6. In front of each manger is shown a horse 7 or a cow 8, each of which has a strap 9 (see also Fig. 4) fastened about the neck with one end, the other end provided with a ring 10 engaged by the projecting end of a sliding bolt 11, at the point where the latter crosses a notch 12 in the front edge of the manger. Each bolt is slidably mounted in the edge of the manger and has a lateral catch 13 projecting out of a slot 14 so it may be operated either by hand or by a lateral finger 15 fixed on a suitably mounted slideable rod 16. Each bolt is pushed forward by a compression coil spring 17 in rear of it.

Connected to the front end of rod 16 is

a light wire cable 17^a which is guided over a sheave 18 and has its outer end passed upwardly and secured to a lever 19, which springs on a pivot 20 fixed in the stable wall. 60 From the swinging end of the lever also extends a short cord, chain or other strand 21, to the lower end of which is attached a pin 22 (see Fig. 1). This pin normally rests in a staple 23, in front of a hasp 24, which is hinged at 25 to the sliding stable door 26. This door is hung by rollers 27 riding on a rail 28 in the usual manner. The door is normally pulled open by a weight 29 and a guided cable 30 having one end attached to the rear edge of the door as indicated at 31 in Figs. 1 and 2. This weight will act and open the door as soon as the pin 22 is raised out of the staple 23, because the staple is leaning toward the door so that the slant 23^x 70 of it (see Fig. 5) causes the hasp 24 to escape when the weight 29 pulls after pin 22 is removed. The weight 29 may be arranged inside the stable but is in the drawing shown as disposed in a housing 29^a. The same is true of the main weight 32 in the inclosure 32^a to the right in Figs. 1 and 2.

The weight 32 is suspended from a cable 33 resting on a pulley 34, slideable on a shaft 35. The upper end of the cable is secured to and wound on a drum 36, which is fixed on a shaft 37, journaled at 38 in the front wall of the stable and in a frame arm 39. 80

Fixed upon the front end of shaft 37 is a disk 40 carrying a pin 41, and near the middle of the shaft is fixed a cog wheel 42 driving a pinion 43 fixed on a lighter shaft 44 on whose rear end is fixed a disk 45 having a circular row of pins 46, one of which (46^a) is extra long. 90

Mounted within the inclosure 32^a is a bell 47 the sound of which can be readily heard through apertures 48 in the walls of the inclosure or shell which will rather increase the sound. 100

The bell is sounded by a hammer 49 which has its arm 50 pivoted at 51 and is provided with a cam or tooth 52 (see Fig. 3) operated by the pins 46 of the disk. A spring 53 tends to throw the hammer against the bell and a lighter spring 54 lifts the hammer from the bell to let the latter vibrate the moment it has been struck, meanwhile the next pin 46 comes along and completes the raising of the hammer for the next stroke. 105

Pivoted at 55 in an aperture 56 of the adjacent wall or any other suitable point is a 110

lever 57 having a lateral tooth 58 arranged to normally engage the long pin 46^a and hold the ringing mechanism idle and thereby also the drum 36 and disk 40 idle. Lever 57 is held in said position by one end of an easily combustible cord 59, which is slidable in staples, or it may be sheaves 60, and has its other end secured at 61. The cord 59 is thus arranged and extended into most 10 parts of the space above the cattle so as to be burned by fire started any place in the stable, and should an abnormal heat precede the actual presence of fire in the stable, such heat will melt fuses 59^a by which sections of 15 the string are united and whenever said string is severed the lever 57 will be swung so as to release the long pin 46^a. Such swinging is effected by a cable or a soft wire 62 which extends from the lever 57 over a 20 guide pulley 63 and having a weight 64 suspended from the end passed over the pulley.

The stable is supplied with water under pressure from a regular water system or from an elevated tank (not shown) filled 25 from a pumping device driven by a wind mill or other motive power (not shown).

The device supplying drinking water to the cattle involving no part of my invention I will not describe the means, but will 30 say that in Fig. 1, 65 designates the water supply pipe entering the stable under control of a valve 66, which when turned by a downward push of a rod 67 and link 68 admits the water into pipes 69, 70, 71, 72 and 35 73. The latter two pipes are provided each with a series of apertures 74 from which water will stream as 75 downward into the mangers and upward so as to spread onto the fire, and forward against the animals 40 to drive them from their stalls or places as soon as they have been released.

In Figs. 1 and 2, 76 designates a pig pen within the stable and having its top provided with slits 77 for the water streams 75 45 to enter. 78 designate the pigs. This pen has two doors 79, 79^a hinged at 80 and may be thrown open by springs 81 or other automatic means. The door 79^a is slightly overlapped by door 79 and the latter is held 50 closed by having a pin 82 engaged by a hook 83, which is pivoted at 84 and has an arm 85 connected by a wire 86 to a radial arm 87 of a vertical shaft 88, which has another radial arm 89 engaged by a pin 90 fixed in the sliding 55 rod 16.

In the operation of the device whenever the cord 59 becomes severed either by fire or by heat from an approaching fire, the weight 64 will cause lever 57 to swing and 60 release the escapement wheel 45. The shaft 37 being now rotated by the drum 36 and

weight 32, the bell will start ringing and keep on ringing until the weight 32 reaches the floor or ground. This takes some time since the ringing mechanism acts as a speed 65 governor. The first half turn or less of the disk 40 causes pin 41 to raise lever 19 to its upper position where it is held by a spring catch 91 (see Fig. 1). The next half turn or less of the disk 40 causes pin 41 to press downward on the top end of rod 67 so as to turn on the water at valve 66. Rod 67 remains down and lever 19 raised until brought back by an operator. Hence the disk is free 70 to rotate with the drum and thus allow the 75 ringing to continue as long as possible.

The moment the lever 19 was raised by pin 41 the cord 21 raised the pin 22 and let the stable door spring open. The lever 19 also pulled at cable 17 and caused rod 16 to slide and release all the rings 9 holding the horses and cows. And the sliding of rod 16 caused the vertical shaft 88 to turn sufficiently to operate hook 83-85 and the springs 81 opened the doors for pigs, sheep 80 or other small live stock contained in pens. As the water is streaming in upon the animals in directions tending to drive them out 85 of the stable and the large bell 47 is ringing the animals are not only at liberty to escape 90 but are induced to do so. And yet it may be well for the owner to once in a while train the animals by false alarms to get in the habit of hurrying out of the building when the alarm is sounded, about the same as is done in training horses for service in a fire 95 department station.

Another and main object of the bell ringing is of course to call people to extinguish the fire.

100

What I claim is:

1. In an apparatus of the class described, a slidable door and means tending at all times to open the door, a staple in the adjacent part of the stable wall, a hasp hinged to the door and having a slot to go upon the staple, and a pin inserted in the staple to hold the hasp engaged, said staple being inclined toward the door opening so as to automatically release the hasp when the pin is removed, the door opening means causing the door to slide and thus pull the hasp along the incline of the staple and cause it to escape therefrom.

2. The structure specified in claim 1 and a motor having operative connection with the pin to pull it out of the staple, means normally holding the motor in check, and means which when subjected to a predetermined degree of heat release the motor.

105

In testimony whereof I affix my signature.
KARL RADOUSH.
